ATTORNEY

UNITED STATES PATENT OFFICE.

WILLIAM A. KIMBELL, OF BIRMINGHAM, ALABAMA.

DRAFT-SPRING.

1,172,803.

Specification of Letters Patent. Patented Feb. 22, 1916.

Application filed July 21, 1915. Serial No. 41,166.

To all whom it may concern:

Be it known that I, WILLIAM A. KIMBELL, a citizen of the United States of America, residing at Birmingham, in the county of 5 Jefferson and State of Alabama, have invented certain new and useful Improvements in Draft-Springs, of which the following is a specification.

My invention relates to draft spring attachments for plows, vehicles, etc., and consists in the novel arrangement of the spring holder parts which permit the spring to be readily assembled between them and which are designed to dispense with the use of 10 split links for connecting the draft spring in service position. To avoid the necessity of split links to connect up the draft spring attachment, at least one member of the 15 spring holder must be disposed without the 20 spring so that it may be assembled in operating position with the spring without having to pass its body portion through the spring. The difficulty with the use of 25 an external holder member is in providing 30 means which will hold it against falling away from the spring without interfering with its quick attachment to or removal from the spring. This I have accomplished by providing the outer member of the 35 spring holder with an inner leg adapted to be passed through the spring and by engagement therein and with the member to prevent the latter becoming disengaged from the spring by a movement other than length- 40 wise of the spring. Preferably this inner leg is inclined so as to engage the top or bottom of the spring and support the outer member substantially centrally of the spring while the reversely acting holder member 45 is passed through the spring and disposed on the opposite side of the outer member from that on which its said leg is disposed so that the latter member is held by its leg and the inner member against lateral 50 displacement relatively to the spring.

With these objects in view my invention comprises in its preferred construction the arrangements of parts which are hereinafter described, reference being had, for purposes 55 of illustration, to the accompanying drawings which form a part of this specification, and in which:—

Figure 1 is a side elevation of the draft spring attachment in service. Fig. 2 is a 55 plan view of Fig. 1. Fig. 3 shows the outer

holder member and spring assembled with the inner member detached.

Similar reference numerals refer to similar parts throughout the drawings.

As illustrated, my draft spring attachment is shown interposed between the whiffle tree 1 and the beam 2 of a plow, the latter having a clevis 3 detachably fastened on its forward end by a nut and bolt 4. A solid link 5 is made fast at the center of the whiffle tree and may be of any standard construction, but does not have to be split. The draft spring attachment comprises a coiled draft spring 6 which is held in position in the frame or holder formed by an outer frame member 7 and an inner frame member 8 which engage opposite ends of the spring and are relatively movable to compress the spring between them. As these members require special construction in order to accomplish the objects of my invention, I will describe them more in detail, as follows: The outer holder member is formed of strong wire bent to a U-shape and having at the free end of one side 75 thereof an inwardly and reversely bent hook 9 and opposite it having the free end of the other side bent inwardly and elongated to form a leg 10 which extends forward through the spring and preferably to a 80 point beyond the U-bend of the member 7. The inner member 8 being adapted to be passed through the spring can be of any suitable design, but is preferably formed of wire bent to a U-shape with its sides 85 brought more closely together so that they can be passed through the spring and will yieldingly engage the spring so as to be held thereby in a diametrical plane across the spring. The free ends of its sides are 90 bent outwardly and rearwardly to form hook members 11 which engage one end of the spring.

In assembling the parts the hook end 9 of the outer member 7 is first passed 100 through the link 5 and then the spring is placed under the member with the leg 10 of the latter inserted in the spring which is then moved toward the open end of the member until it engages in the hook 9 and 105 the bend at the forward end of the leg 10. The member 7 is then forced downwardly about the spring until its leg 10 engages the under side of the spring and thus prevents the member 7 moving substantially below 110

the horizontal central plane through the spring. The end of the leg 10 projects under the bend of the member 7 and will prevent it swinging downwardly sufficiently 5 to fall substantially below the axial center line of the spring. This extension also serves to positively prevent the U-bend of the outer member 7 from swinging down below the adjacent end of the spring in case 10 the down pull thereon is more than enough to overcome the tension of the member 10 against the bottom of the spring. The inner member 8 is then contracted and inserted through the spring and its hooks 11 15 caused to engage the forward end of the spring above the member 7 so that they prevent the latter member cocking upwardly. In this position the U-bend of the inner member 7 projects sufficiently beyond 20 the spring to be engaged in the clevis when the latter is detached from the beam and after being adjusted to the desired point in the clevis the latter is reattached to the beam. Under these conditions it will be 25 noted that no split links are required, that the parts can be readily assembled and detached and that the draft spring attachment is produced in the most compact design and affords the shortest possible connection 30 between the whiffle tree and the plow beam or vehicle tongue.

What I claim as new and desire to secure by Letters Patent, is:—

1. A draft spring device comprising in combination, a coiled spring and a holder therefor comprising an inner U-shaped member adapted to be inserted through the spring and having hooks at its free ends to engage one end of the spring, and an outer 35 U-shaped member having at its free ends hook members inturned to engage the other end of the spring, one of these hook members having a forward extension which projects for a substantial distance through the 40 spring and by engaging the inner walls thereof is adapted to prevent the sidewise disengagement in one direction of said outer member from the spring, said inner member being disposed to prevent the sidewise 45 disengagement of said outer member in the opposite direction.

2. A draft spring device, comprising a coiled spring and a two-part spring holder, one part comprising a U-shaped inner member which is inserted endwise through the 55 spring and provided with out-turned hooks at its ends to engage one end of the spring,

the body of said member being in engagement with the inner wall of the spring, and the other part comprising an outer U-shaped member, the sides of which are adapted to snugly receive the spring between them, and the U-bend of which is disposed at the opposite end of the spring from the U-bend of the inner member and in position to be stopped against upward play by the out turned hooks of said inner member, the sides of said outer member having their ends inturned to engage the other end of the spring and under the U-bend of the inner member, and one of said ends being bent forwardly and at an incline downwardly so as to project through and engage the inner wall of the spring.

3. The combination, in a draft spring device, with a draft spring and a member which passes through the spring and is provided at one end with means to engage one end of the spring, of an outer removable frame member which is formed of a bent metal rod, the body of which is U-shaped and adapted to receive the spring and the free ends of which are inturned and bent to engage the other end of the spring, one of said bent ends being extended forward and adapted to pass through the spring to a point beyond the U-bend of the member, substantially as described.

4. In combination, a coiled spring, a U-shaped inner member adapted to be passed through the spring and to yieldingly engage the inner wall thereof, out-turned hooks at the free ends of said member to engage one end of the spring, a U-shaped outer member adapted to fit snugly about 90 and to yieldingly engage the outer wall of said spring, inturned hooks at the free ends of said outer member disposed to engage the outer end of said spring, the hooks of each member serving as stops to hold the other member in position in the spring, and a forward extension of one of said latter hooks which is inclined away from the plane of the inner member and is adapted to engage the inner wall of the spring, and to project beyond the U-bend of the outer member and on the opposite side thereof from the inner member, substantially as 95 and for the purposes described.

In testimony whereof I affix my signature.

WILLIAM A. KIMBELL.
